INTERLOCKING PANEL JACKET STRUCTURE
FOR AIR CONDITIONING AND HEATING
EQUIPMENTSamuel J. Levine, West Orange, N. J., assignor to
General Electric Company, a corporation of
New York

Application December 20, 1946, Serial No. 717,492

2 Claims. (Cl. 126—114)

1

The invention relates to panel jackets suitable for enclosing air conditioning apparatus or the like while providing ready access to the apparatus for servicing, repair, and replacement of parts.

The invention relates particularly to interlocking flanged edge sheet metal panel jacket structures suitable for a forced circulation warm air furnace requiring, among other things, detachably interconnected back, side, and top panels and a readily removable front access door panel, cold air inlet and warm air outlet sections inside the jacket with the transverse sectionalizing partitions carried by the jacket side panels for supporting the furnace parts inside the jacket and also metal radiation screens mounted in inner spaced apart relation with the jacket walls around the combustion chamber to provide confined air space thermal insulation.

One object of the invention is to provide an improved form of integral re-enforced rabbeted corner column interlocking rectangular panel jacket assembly that is particularly adapted for meeting the various warm air furnace requirements of the character indicated above and still can be used with advantage for enclosing other forms of air conditioning apparatus or the like if desired.

A particular object is to provide an improved rectangular jacket structure formed of complementary interlocking pairs of cornerwise abutting thin sheet metal panels having flanged edges with each corner of the jacket re-enforced by a triple right angle bending of each vertical edge of an opposing pair of side panels into inwardly facing channel conduit columns with an angle strip extension therefrom to impart substantial load bearing strength and form retaining stiffness to the entire jacket structure in addition to providing relatively tight rabbet joints for a readily removable front access door panel as well as a detachable back panel and also providing an inner spaced apart panel or screen and transverse partition attachment and bracing strip as well as a through longitudinal conduit useful for piping or electric wiring at each corner of the jacket.

Further objects and advantages of the invention will appear in the following description of the accompanying drawing in which the single figure is a perspective view partially broken away in section to show the details of a rectangular sheet metal interlocking panel jacket embodying the improvements of the present invention in a preferred form and adapted for enclosing a gas fired forced circulation warm air furnace.

The improved rectangular sheet metal jacket

of the figure is provided with complementary interlocking pairs of opposing rectangular panels having flanged edges comprising as shown the two opposing side panels 10 and 11, the detachable rear panel 12 and the front readily removable access door panel 13. In the preferred form shown the front access door panel 13 is divided into two parts, 13a and 13b. Since the gas fired warm air furnace enclosed in the jacket of the type shown is intended to be factory assembled and shipped as a unit, the jacket is provided with an attached bottom plate 14. The jacket top panel 15 covers only part of the top so as to provide space for the warm air outlet opening 16. The side panel 10 has a series of right angle bends in the vertical edges thereto to form inwardly facing corner channel conduit columns 18 with inner angle attachment strip extensions 19 so as to impart substantial load bearing strength and form retaining stiffness to the entire jacket structure as well as provide relatively tight rabbet joints for the detachable back panel 12 and the readily removable front access door 13. The opposing side panel 11 is formed in the same way and the two side panels 10 and 11 are aligned in opposition by means of the several spaced apart transverse members that are attached to and extend therebetween. Thus the bottom plate 14 has the flanged edge 14a abutting against the inside of the side panel 10 and secured thereto by suitable screws or bolts 17. In the same way the opposite flanged edge 14b is secured to the side panel 11. The other flanged edges 14c and 14d of plate 14 are each secured by screws or bolts to the inner attachment strip 19 so as to brace the two side panels 10 and 11 in spaced apart upright opposing relation. In the same way, the intermediate partition 20 has its flanged edges secured to the two opposing side panels 10 and 11 and the corresponding attachment strips 19 thereof. In addition the two spaced apart Z strips 22 and 23 are secured by screws to and extend between the attachment strips 19 at the rear vertical edges of the side panels 10 and 11 so that the rear panel 12 may be detachably interconnected in edgewise abutting relation with the rabbet corner joints provided by the combined channel conduit columns 18 and the angle extensions 19. The rear panel 12 is detachably secured in place by screws engaging with the transverse Z members 22 and 23.

The intermediate transverse partition 20 divides the furnace jacket into two compartments B and C. In the upper compartment C the gas fired combustion chamber and heat transfer sur-

faces, not shown, are to be mounted and supported jointly by the transverse partition 20 and the top panel 15 which is provided with a flue outlet opening 24 to form a surrounding hollowed-out mounting well for the flue connection of the gas fired furnace.

In the lower compartment B of the furnace jacket the air circulating blower 25 indicated by dotted lines is mounted together with its driving motor, not shown. Preferably, the blower scroll 25 is suspended directly from the transverse partition 20 with a suitable opening 26 cut through the partition for projecting air from the scroll 25 upwardly over the heat transfer surfaces enclosed within the upper compartment C.

The improved interlocking jacket structure makes it easy to provide adequate heat insulation around the furnace combustion chamber and heat transfer parts enclosed within the upper compartment C. Thus the thin sheet metal radiation screen 30 extends between the partition 20 and the top of the jacket in inner spaced apart but tight relation with the jacket side panel 10, since the vertical edges of screen 30 are inwardly flanged so as to fit in matching engagement with the inner angle extensions 19. The opposite side panel 11 is provided with a similarly spaced apart and supported radiation screen 31. Likewise the back panel 12 is heat insulated by means of an inner radiation screen 32 which is mounted on the outside of the inner angle extensions 19 so that the screens 30, 31 and 32 may be secured to the angle extensions 19 by the same fastening screws. The top panel 15 has downwardly flanged edges and is provided with an inner heat insulating radiation screen 33 with the top radiation screen 33 and the top panel 15 held in place on top of the furnace structure by holding screws passing through central openings 35 with the edges supported along the top edges of the radiation screens 30, 31 and 32. The edges of the top radiation screen 33 are formed so that this screen will abut tightly against the top channel edges of the inside panels 10 and 11 and also against the upper edge of the back radiation screen 32 in relatively airtight sealing relation. The projecting part 30a of the radiation screen 30, together with the corresponding projecting part 31a of the opposite radiation screen 31 and the up turned edge 33a of the top radiation screen 33 and also the upper edge of the front radiation screen 37 form a rectangular collar that enables a warm air distribution duct to be attached tightly to the furnace jacket.

The upper front radiation screen 37 is secured to the outside of the front angle attachment strips 19 in the same way as the back radiation screen 32. The narrow upper rounded front lintel screen 38 is secured along with the radiation screen 37 and extends transversely between the side panels 10 and 11 in alignment with the upper edge of the upper access door 13a and carries suitable spaced apart spring catches 39a for frictionally engaging with the upper end of the door 13a to hold the door in the closed position in which the flanged vertical edges of the door engage with the opposing pair of rabbet joints provided by the opposing front corner channels 18 and the angle extensions 19. The bottom door 13b is provided with bent-over hooked sections 39 and 43 for engaging respectively with the front flanged edges of the bottom plate 14 and the flanged edges of a dropped floor 20a of a vertical dividing wall 44 attached to the intermediate partition 20. Similarly the lower edge of the

upper door 13a is provided with a cooperating over-hanging hooked portion 41 for detachably mounting the door with its edges in the rabbet joints formed by the front corner columns of the side panels. Thus it is only necessary to pull the upper end of the upper door 13a forward to release the spring catches 39a to enable the door to be readily detached from the jacket structure. After the upper door 13a is removed, the supporting hooks of the lower door 13b then can readily be detached.

The recessed vertical dividing wall 44 with the sloping extension 44a and the inner radiation screen 45 joining the upper front radiation screen 37 are provided for enclosing the front of the combustion chamber and heat transfer surfaces in the compartment C and thus serve as radiation screens. The edges of the vertical wall 44 and sloping extension 44a are flanged so as to be interconnected by suitable screw fasteners in tight relation with the side radiation screens 30 and 31. This provides a control chamber D with a dropped floor 20a between the upper front door 13 and the vertical dividing wall 44 for installation of the gas furnace control and pressure regulating valves, not shown, that are connected with the burners extending through the opening 42 in the vertical wall 44. The upper door panel 13a is provided with suitable slots 43 for admission of combustion air into the control chamber and through the opening 42 to the burners.

A cold air inlet into the furnace jacket may be cut in either or both of the side panels 10 or 11 as required by the installation for admission of return air into the blower compartment B.

Where the improved interlocking flanged edge sheet metal panel jacket structure of the present invention is to be used to enclose other forms of air conditioning apparatus, in which the bottom plate 14 and the intermediate partition 20 are not required, then it is only necessary to provide suitably spaced apart transverse angles or Z members similar to the members 22 and 23 for engaging with the hooked edges of the removable front access doors 13a and 13b with these transverse members attached to and braced by the angle extensions 19 of the aligned side panels 10 and 11. Furthermore, if desired, the front access door may be formed in one solid piece rather than in two parts. In each case, the corner columns 18 provide conduits extending from the top to the bottom at each corner of the jacket for receiving piping or electric wiring for ready connection with the air conditioning apparatus enclosed within the jacket.

What I claim as new and desire to secure by Letters Patent of the United States is:

1. A jacket for air conditioning apparatus and the like comprising pairs of oppositely facing rectangular panels defining a rectangular enclosure, each panel of one of said pairs of panels having its edges at the corners of said enclosure bent along spaced parallel lines to form a pair of oppositely facing inwardly opening channels and attachment strips extending from the inner edges of said channels normal to and away from the panel, said channels constituting corner columns for said jacket, the corresponding edges of the panels of another of said pairs being bent to provide flanges fitting within the corners formed by said channels and said attachment strips whereby rabbet joints are provided at said corners, means including transverse members attached to said strips for connecting the

panels of said first pair, means for securing the panels of said second pair in engagement with said corner columns, and metal screens spaced from said jacket and carried by and extending between said corner columns inside said jacket to provide heat insulating air spaces between said screens and the walls of said jacket.

2. A unitary enclosing jacket and supporting structure for an air conditioning apparatus comprising pairs of oppositely facing rectangular panels defining a rectangular enclosure, each panel of one of said pairs of panels having its edges at the corners of said enclosure bent along spaced parallel lines to form a pair of oppositely facing inwardly opening channels and attachment strips extending from the inner edges of said channels normal to and away from the panel, a transverse floor member having flanged edges secured to said attachment strips for providing a bottom for said enclosure, a transverse member having an air outlet opening and arranged at the upper extremity of said panels to provide a top for said enclosure, an inter-

mediate partition attached to a pair of said panels for dividing said enclosure into compartments and for supporting air conditioning apparatus in at least one of said compartments, and metal screens attached to said strips and in spaced relation with said panels to provide heat insulating spaces between said screens and said panels of at least one of said compartments.
